Des. 242,210

Patented Nov. 9, 1976

242,210

COMBINED VACUUM CLEANER AND STEAM CLEANER UNIT

Carl Parise, 3685 Downey Ave., Reno, Nev. 89503, and
James M. Wimsatt, 155 Pintail Drive, Carson City,
Nev. 89701

Filed Jan. 20, 1976, Ser. No. 650,656

Term of patent 14 years

Int. Cl. D7—05

U.S. Cl. D15—52

FIG. 1

FIG. 2

FIG. 3

FIG. 4

FIG. 5

FIG. 1 is a perspective view of a combined vacuum cleaner and steam cleaner unit showing my new design:

FIG. 2 is a side elevational view thereof;

FIG. 3 is a top plan view thereof;

FIG. 4 is a right end elevational view thereof;

FIG. 5 is a bottom plan view thereof.

The cord has been shown fragmentarily in FIGS. 2, 3 and 4 for convenience of illustration.

I claim:

The ornamental design for a combined vacuum cleaner and steam cleaner unit, as shown and described.
